UNITED STATES PATENT OFFICE.

JAMES R. MOFFATT, OF OAK PARK, ILLINOIS, ASSIGNOR TO UNION SPECIAL MACHINE COMPANY, OF CHICAGO, ILLINOIS, A CORPORATION OF ILLINOIS.

LOOP-RETAINER FOR SEWING-MACHINES.

1,097,041.

Specification of Letters Patent.

Patented May 19, 1914.

Application filed May 23, 1912. Serial No. 699,217.

To all whom it may concern:

Be it known that I, JAMES R. MOFFATT, a citizen of the United States, residing at Oak Park, in the county of Cook, State of Illinois, have invented certain new and useful Improvements in Loop-Retainers for Sewing-Machines, of which the following is a description, reference being had to the accompanying drawing and to the figures of reference marked thereon.

My invention relates to improvements in sewing machines, and particularly to a construction of throat plate and loop retainer with means for supporting and adjusting the loop retainer attached to the under side of the throat plate, the purpose of which loop retainer is to retain the loops of needle thread far enough to the right to allow the formation of the triangular spaces, between the backs of the loopers, the looper threads on the left and the needle threads on the right,—into which the needles must descend.

I have shown my invention as applied to the throat plate of a flat bed machine in which two pairs of slabbed shank needles arranged at points oblique to each other respecting the line of feed are employed, with two loopers coöperating therewith to form stitches, but it will be understood that I do not wish to be so limited.

It is a matter of considerable nicety to properly adjust the loop retainers, they being secured on the under side of the throat plate, and heretofore it has been necessary to approximately adjust them to position by loosening the set screws on the under side of the throat plate, which means removal of the throat plate from the machine, adjusting them lengthwise, then replacing the throat plate in the machine, and it is sometimes necessary to repeat this operation several times.

The object of the present invention is to provide a throat plate and a loop-retaining device which can be readily adjusted thereon.

The invention is illustrated in the accompanying drawings, in which—

Figure 1 is a perspective view of a throat plate having my improved means for securing loop retainers thereto, the needles and loopers being shown in outline, the parts being adapted to the well known Union Special two-line machine; Fig. 2 is a sectional

side view; Fig. 3 a bottom plan view; and Fig. 4 is a perspective view of a sewing machine embodying the invention.

In these drawings, 1 represents the needles and 2 the coöperating loopers. The throat plate is shown at 3, and has the openings 4 for the passage of the needles, and the slots 5 for the passage of the feed dogs. On the under side of the throat plate are longitudinal slots 6, in which the loop retainer shanks 7 are set, being retained by the set screws 8, which pass into the throat plate from the under side, the inner faces of the heads of the screws clamping the loop retainers in place. At their outer ends, the shanks of the loop retainers are bent as at 9 to extend through the throat plate slots 5, which are cut through the throat plate, whereby the loop retainers may be shifted longitudinally after the set screws have been loosely clamped on the retainers. The inner or upper ends of the set screws 7 are nicked, so as to be engaged by a screw driver, by which they may be manipulated from the top of the throat plate and thoroughly tightened. The small screws 10 pass through the throat plate and bear upon the forward or spring portion of the retainers, thus giving a slight vertical adjustment thereto, and one of the loop retainers has its end 11 bent at an angle to the body.

In operation, the shanks of the retainers are inserted in the longitudinal slots of the throat plate, and the screws 7 tightened to hold them from dropping out; the throat plate is then placed in position in the machine, and the retainers adjusted longitudinally to correct position by manipulation of the upwardly projecting portions 9 of the shanks. The screws 7 are then tightened from the upper side of the throat plate, and any slight vertical adjustment accomplished by the screws 10.

Having thus described my invention, what I claim as new and desire to secure by Letters Patent, is:—

1. In a sewing machine throat plate, a loop-retaining device located beneath the throat plate and means for permitting said loop-retaining device to be adjusted longitudinally while said throat plate is in operative position.
2. In a sewing machine throat plate, a

- loop-retaining device, means for securing said loop-retaining device, said means including a single member operable from both sides of said throat plate.
5. 3. In a sewing machine throat plate, a loop-retaining device, means for securing said loop-retaining device to the under side of the throat plate, said means including a device operable from both sides of said 10 throat plate.
4. In a throat plate for sewing machines, a loop-retaining device, guiding means for said loop-retaining device, said guiding means being extended to the outer edge of 15 said throat plate.
5. In a throat plate for sewing machines, a loop-retaining device, guiding means for said loop-retaining device, said guiding means extending from one side of said 20 throat plate to another.
6. In a throat plate for sewing machines, a loop-retaining device, means for permitting said loop-retaining device to be adjusted longitudinally, and means to hold 25 said retaining device in proper vertical position during the adjustment thereof.
7. In a sewing machine, a bed plate, a throat plate, and means to support said throat plate, said throat plate being provided with a loop-retaining device on its 30 lower side, means for permitting adjustment of said loop-retaining device, said means being accessible without removing the throat plate from its support.
35. 8. The combination of a throat plate for sewing machines, with a loop-retaining device, and means for securing said loop-retaining device beneath the throat plate, said throat plate having an opening at its 40 edge and said loop-retaining device having its shank bent at an angle and extending into said opening.
9. In a throat plate for sewing machines, a loop retainer, a groove for said loop retainer, means to hold said loop retainer in 45 said groove, said loop-retaining device carrying means for permitting its longitudinal
- adjustment while the throat plate is in operative position.
10. In a throat plate for sewing machines, 50 a loop-retaining device, means to adjust the vertical position of the free end thereof, and means to permit its longitudinal adjustment while the throat plate is in operative position. 55
11. In combination with a sewing machine throat plate, a loop retainer, and means for securing the retainer to the throat plate, comprising a clamping screw secured to the throat plate, and means for operating said 60 screw both from its head and from the shank.
12. In combination with a sewing machine throat plate, a loop retainer, a screw projecting upward from the bottom of the 65 throat plate and having a clamping head to clamp the retainer in position, said screw being provided with means on its upper end, whereby it may be manipulated and tightened or loosened from the upper side of the 70 throat plate.
13. The throat plate having a slot in its under side for the shank of the loop retainer, a clamping screw inserted from the under side of the throat plate to hold the 75 shank in its slot, the opening in the throat plate to receive the clamping screw extending through the throat plate, and the upper end of the screw being adapted to be operated by a screw driver or other tool, the 80 shank of the retainer having an upwardly extending end portion, said throat plate having an opening leading from said longitudinal slot and adapted to receive said upwardly extending end, and a screw for adjusting the forward free end portion of the 85 loop retainer.

In testimony whereof, I affix my signature, in the presence of two witnesses.

JAMES R. MOFFATT.
